UNITED STATES PATENT OFFICE

GEORGE HILGER, OF CHICAGO, ILLINOIS

REFRIGERATING SYSTEM

Application filed April 13, 1927. Serial No. 183,249.

The present invention relates generally to an improved type of refrigerating system and is more particularly applicable to a spray type refrigerating system adapted for use in 5 relatively large cooling rooms, such as are customarily used in retail meat markets.

It is an object of the present invention to provide a new and improved refrigeration system for use in coolers and the like wherein 10 a compact spray refrigeration unit is mounted in the central upper portion of the cooler so as to provide increased overhead storage space therein by making possible the use of the space at either side of the cooling unit 15 which is usually entirely occupied by such cooling systems; incidentally providing thereby a larger open space for the free circulation of the cooling currents.

Still another object of the invention is to 20 provide auxiliary cooling compartments or chambers in which various temperatures below that in the main room may be obtained, access to said auxiliary chambers being attained through the open spaces provided at 25 either side of the cooling unit.

A further object of the invention is to provide a spray refrigerator system which is capable of maintaining continued cooling action after the spray system has ceased to 30 operate.

Further objects and advantages will become apparent from the following description and in the accompanying drawings, in which:

25 Figure 1 is a vertical section taken on the line 1-1 of Fig. 2 of a refrigerating system embodying the features of my invention.

Fig. 2 is a vertical section taken on the line 2-2 of Fig. 1.

40 Fig. 3 is a horizontal section taken on the line 3-3 of Fig. 1.

Fig. 4 is a plan view of the system with the tops of the cooler and the spray tank removed.

45 While I have shown in the drawings and will describe herein the preferred embodiment of the invention it is to be understood that the invention is not to be limited thereby to the particular form disclosed, but that it is my intention to cover all the modifications 50 and alternative constructions which fall

within the spirit and scope of the invention as expressed in the appended claims.

In the disclosure of the preferred embodiment of my invention, I have shown generally a cooler having walls 10, top 11 and floor 12 each of which are heat insulated in any suitable manner. Disposed within the cooler are various means, such as the hooks 13 and the shelf 14, for receiving the food stuffs to be kept therein and these 55 means are preferably positioned to permit free circulation of air about the room. If desired a window 15 may be provided in the walls of the room with an entrance thereto provided by means of a suitable door 16. 60

In attaining the objects of the invention, a spray refrigeration unit is mounted in the cooling room with an air-current-directing or baffle means so disposed with relation to the unit as to assist the artificial circulation 70 of air set up thereby and to direct the natural currents of air caused by convection when the system is not in operation. To this end the spray system and the baffle means are mounted in the upper portion of the cooling 75 room extending substantially across the central part of the room and providing large spaces of either side for storage purposes, for ready access to the unit and for the unrestricted passage of air. 80

The spray refrigeration unit, in the present instance, comprises a closed water-tight tank having a top 17, bottom 18, sides 19, and ends 20 suitably suspended from the top 85 of the cooling room as by means of the bolts 21. Preferably the tank is relatively narrow and deep to provide the maximum practical width of space between the tank and the walls of the cooler without lessening the 90 cooling power of the unit. Circulation of air through the tank is possible by means of passages which permit the ingress and egress of air to and from the tank, such as the inlet opening 22 in the upper portion of one end 95 of the tank and the outlet ports 23 positioned in the upper portions of the sides of the tank adjacent the opposite end. As shown in Fig. 2, the outlet ports 23 preferably have a tubular duct 24 secured thereto which duct is 100

turned at the end to direct the air from the tank downwardly of the room.

The tank is adapted to hold a substantially large quantity of liquid such as brine or other suitable cooling fluid, with a relatively narrow spraying space provided between the surface of the liquid and the top 17 of the tank. In the present instance the cooling of the liquid in the tank is effected by a coiled 10 pipe 25 which has an inlet 26 and an outlet 27 in or adjacent the air inlet opening 22. The pipe 25 is connected to an outside source of refrigerating agent (not shown) such as the ordinary compression type unit employing 15 ammonia or similar refrigerant. Preferably the inlet side of the coiled pipe 25 enters the tank in the spraying space above the surface of the cooling liquid and has one or more coils 25^a disposed in said space near 20 the outlet ports 23. The remaining coils of the pipe 25 are positioned below the surface of the liquid and extend throughout substantially the entire lower portion of the tank.

The spraying means, by which the air is 25 brought into intimate contact with the cooling liquid, comprises one or more spray nozzles 28 positioned in the spraying space above the surface of the liquid and supplied with cooled liquid from the tank under pressure 30 by a suitable power driven pump 29. In this instance the pipe line 29^a conveying the liquid from the tank to the nozzle 28 is connected to a tank outlet 30 which is located near the end of the tank from which the 35 air is expelled. The spray nozzles 28 are mounted to direct a stream of atomized cooling liquid lengthwise of the spraying space from a point near the inlet opening in the tank. Thus a slow continuous circulation 40 of air is induced which draws the air into the tank through the inlet port 22 over the surface of the cooling liquid in the tank, through a cold zone about the exposed refrigerating coil 25^a, and out through and 45 downwardly from the outlet ports 23.

Most of the cooling liquid introduced and intimately mixed with the air by the nozzles will at once fall into the liquid in the tank to be cooled and used again. It will be noted 50 that the coil 25^a is spaced a substantial distance from the nozzles so as to allow the major portion of the sprayed liquid to drop out before it reaches said coil. Moreover, since the exposed coil of the refrigerating pipe is 55 cooler than the body of the liquid, a cold zone is set up thereabout which further reduces the temperature of the air current set up by the spray and effects a further precipitation of the mechanically carried moisture. Thus 60 the air which is finally expelled into the cooling room will carry very little water in excess of its saturation point.

An auxiliary freezing chamber is provided in the tank and is arranged to be cooled by 65 direct contact with the cooling liquid there-

in. The chamber herein shown is for the purpose of providing ice for other purposes but obviously could be adapted for use, if desired, in freezing any food product or the like. As may be seen in Fig. 1, the coils 25 while extending substantially throughout the interior of the tank, stop short of the outlet end thereof. The unused space thus provided within the tank is substantially filled by a water-tight rectangular shell 31 extending 70 through the tank from one side to the other, and open at each end through the walls of the tank. The shell is of such height as to permit its being entirely submerged in the cooling liquid in the tank. A series of shelf brackets within the shell support a number of sliding trays 32 which are adapted to be inserted from both sides of the tank and to contain the water, food products or the like to be frozen. The use of such a chamber is 75 possible since the substantially large spaces at either side of the spray unit permit of ready access to the chamber openings in the sides of the tank.

The air-current-directing or baffle element 80 which serves to produce a natural movement of the air currents when the spray unit is not in operation comprises, in the present embodiment, a trough shaped shell having two sides 33 and a bottom 34 adapted to underlie and to extend upwardly of each side of the spray tank. Preferably the baffle walls extend upwardly to a point above the downwardly directed discharge opening of the duct 24, so that discharged air will not be diverted into the space between the tank and the baffle. The baffle may be suitably suspended from the top 11 of the cooling room as by means of brackets 35 and, as may be seen in Fig. 2, is spaced from the sides and bottom of the tank to provide substantial air 85 circulating spaces therebetween.

To provide better air circulation the baffle does not extend the full length of the tank but stops short at one end, preferably the outlet end of the tank, as seen at 36. A catch tray or pan 37 having a drain 38 to the exterior of the cooling room underlies the free end of the baffle to remove any water which may be collected thereby.

An auxiliary chilling compartment adapted 90 to cool food stuff or the like below the temperature of the cooling room yet above the temperature of the freezing chamber, may be provided. The compartment herein comprises a rectangular case 39 secured between the side 19 of the tank and the side wall 33 of the baffle with entrance thereto obtained through a suitable door 40 mounted on the baffle wall. As in the case of the freezing chamber the use of such a compartment closely associated with the spray unit is possible only by the provision of the large spaces between the tank and the side walls of the cooler.

In operation the cooling liquid in the tank 95

is held at a suitable temperature by means of the refrigerating coils 25. The nozzles 28 discharge spray through the spraying space above the liquid inducing and setting up a slow continuous current of air which passes out of the tank through the outlet ducts 23 and is directed downwardly of the cooling room. The air, during its induced progress through the room becomes warmer and aids the circulation by naturally rising to the upper part of the room, where it is drawn toward the inlet opening 22 of the tank. Thus a continuing circulation of air is induced, the baffle serving to prevent the cold air surrounding the tank from settling to the floor of the room at any point except immediately adjacent the tank outlet, whereby interruption to the air current stream and cross currents are substantially eliminated.

It is contemplated in this arrangement that at various times, it is desirable to shut off the spray nozzles for sustained periods of time. Such a periodic operation of the spray unit may be controlled by any suitable thermostatic device. In such a system it is preferable that the spray unit be idle as long as possible before the system begins operation again. Thus if means is provided to prolong the periods between operations of the spray unit, a beneficial result has been obtained.

By my construction, a refrigerating system has been provided, capable of generating a reserve supply of refrigeration which will cause the cooled air currents to flow through the room in substantially the same manner as during the operation of the nozzle. This feature is accomplished in the following manner. The temperature in the refrigerating coils 25 is maintained at a point sufficient to congeal the cooling liquid to slush ice. Since the spray tank, which is in effect an ice tank when the spray unit is inoperative, is mounted at the top of the cooling room, the rising warm air will come in contact with and be cooled by the cold surfaces of the tank, whence it will descend to the lower part of the room. As has been pointed out the rising warm air must pass about the baffle before contacting the tank and after it has been cooled will be directed thereby to the open end 36 of the baffle before it is allowed to descend. In this manner a secondary movement of cooling currents is set up in the cooling room while the spray is idle, which currents descend from the unit in the same manner as do the induced currents and then flow upwardly along the walls of the cooler. Thus the system may be shut off for a considerable period of time without any appreciable rise in temperature in the room.

From the foregoing disclosure it will be apparent that I have provided a spray refrigeration system in which a heretofore unused part of the cooler has been turned into an increased area of storage space in the

upper portion of the cooler. An added advantage resides in the simple arrangement of elements which are adapted most efficiently to divert and direct the air currents set up by a spray refrigeration unit and that I have further provided a construction which will cause the air currents to continue the flow within the room after the spray refrigeration unit has ceased operation. Moreover, I have provided a simple arrangement in which three different temperatures, are provided to meet the different refrigerating requirements, namely, freezing, chilling and cooling.

I claim as my invention:

1. A refrigeration system comprising, in combination, a room to be cooled, a tank mounted in the upper portion thereof, a spray refrigerating unit positioned within said tank and adapted to draw air in at one end and to discharge cooled air at the other end, a current directing member embracing and spaced from the bottom and two sides of said tank arranged to direct rising air toward the inlet to said tank, said member being open at the end nearest the outlet side of the tank to permit cooled air to flow therefrom.

2. A refrigeration system having, in combination with a room to be cooled, an enclosed spray refrigerating unit mounted in the upper portion of said room, said unit having an inlet through which warm air is drawn to be cooled and an outlet through which cooled air is discharged, and a baffle member for directing air currents along said spray unit, said baffle member underlying and embracing the sides of said unit and having that portion thereof underlying said outlet opening removed to facilitate the flow of cold air from said baffle member.

3. A spray refrigeration system having, in combination with a cooling room, a closed spray tank mounted in the upper portion of said room having an air inlet and outlet therefor and adapted to contain a cooling liquid, said tank including a refrigerating coil for cooling said liquid, a spray nozzle positioned above said coil for spraying said liquid through said tank whereby to cool the air and generate air currents, a freezing casing positioned in said liquid and accessible from the exterior of said casing, a baffle about said spray tank arranged to permit cooled air to flow downwardly therefrom and to direct warmer air toward the inlet opening of said tank, and a chilling chamber mounted between said baffle and said tank and accessible to the interior thereof through said baffle.

4. A refrigeration system of the type described having, in combination, a room to be cooled, and a spray type refrigerating unit mounted to extend across the upper portion of said room, said unit comprising a closed tank having an air inlet at one end and an air outlet at the other, conducting means on said outlet to direct the cooled air from said

unit downwardly of said room, and an air current directing baffle underlying the lower portion of said tank and extending upwardly of the sides thereof to a point above that at 5 which the air issues from said conducting means.

5. A spray refrigeration system having, in combination, a cooling room, a closed spray tank mounted in the upper portion of said 10 room having an air inlet and outlet therefor and adapted to contain cooling liquid, said tank including a refrigerating coil for cooling said liquid and a spray nozzle connected with a source of cooling medium under pressure and positioned above said coil for spraying said liquid through said tank whereby to cool the air and generate air currents, a baffle spaced from said spray tank arranged to permit cold air to flow downwardly therefrom, 15 and an auxiliary chamber positioned between said baffle and said tank and accessible in a horizontal direction to the interior thereof through said baffle.

6. A spray refrigeration system having, in combination, a cooling room, a spray tank mounted in the upper portion of said room having an air inlet and outlet therefor and adapted to contain cooling liquid to a substantial depth therein, a refrigerating coil in 20 said tank for cooling the liquid, a spray nozzle positioned above said coil for spraying liquid through said tank above the normal level of liquid therein whereby to cool the air and generate air currents, a pump connected to 25 one end of said tank below the liquid level and arranged to withdraw liquid from said tank and to force said liquid to said nozzle under pressure, and a freezing chamber mounted in said tank so as to be positioned 30 in the liquid in said tank adjacent said pump-supply connection, said chamber opening in a horizontal direction through the side of said tank.

In testimony whereof, I have hereunto affixed my signature.

GEORGE HILGER.
